V. ROSENHAGEN

CENTRIFUGAL PUMP

Filed April 19, 1924

2 Sheets-Sheet 2

UNITED STATES PATENT OFFICE.

VICTOR ROSENHAGEN, OF BELLEVUE, KENTUCKY.

CENTRIFUGAL PUMP.

Application filed April 19, 1924. Serial No. 707,730.

To all whom it may concern:

Be it known that I, VICTOR ROSENHAGEN, a citizen of the United States of America, and a resident of Bellevue, in the county of Campbell and State of Kentucky, have invented new and useful Improvements in a Centrifugal Pump, of which the following is a specification.

My invention relates to centrifugal fluid pumps, especially those adapted for operation upon fluids such as oil and water that may be used for lubricating machine tools and the like.

An object of my invention is to provide a device of the class described that is adapted to provide a water flow of fluid at a minimum pressure.

Another object of my invention is to provide a device of the class described for the purpose stated, especially adapted for use with machine tools.

These and other objects are attained by the means described herein and disclosed in the accompanying drawings, in which:

Fig. 1 is a sectional view through a pump embodying my invention.

Fig. 2 is a sectional view on line 2—2 of Fig. 1 looking in the direction of the single headed arrow.

Fig. 3 is a sectional view on line 3—3 of Fig. 1.

Fig. 4 is a sectional view on line 4—4 of Fig. 1.

Fig. 5 is a sectional view on line 5—5 of Fig. 1.

Fig. 6 is a sectional view on line 2—2 of Fig. 1, looking in the direction of the double headed arrows.

My device comprises a casing 10 consisting of an upper housing 11 and complementary lower housing 12. The lower or major portion of the casing is adapted to be deposited within a receptacle 13 to which the lubricant employed with a machine tool or the like may flow and from which receptacle the fluid may be passed to the cutting tools associated with machine tools. The bottom housing 12 is provided with suitable depending legs or lugs 14 for supporting the device within the receptacle 13 and also serve to space the aperture 15 within the lower face of the housing 12 from the bottom of the receptacle 13 so that the fluid upon which the pump operates may find its way into the casing from the receptacle. The upper hous-

ing has apertures 150 formed in it. The apertures 15 and 150 establish communication between the receptacle 13 and the rotor chamber 16 formed within the casing 10. A rotor 17 disposed within the rotor chamber 16 is carried by a shaft 18 that extends upwardly beyond the casing 10 and receptacle 13 and may carry at its upper end any suitable means such as a bevel gear 19 which bevel gear may be actuated by a machine tool or the like in any suitable manner and by any suitable means. By reference to the plan view of the bottom housing 12, disclosed in Fig. 6, it will be observed that there is provided a central downwardly extending recess 20 that constitutes part of the rotor chamber and that said recess is defined on opposite sides by a pair of upwardly extending walls or ribs 21 and 22 that set off portions of the recess 20 from the ways 23 and 24 constituting parts of the rotor chamber and lying outwardly of the ribs 21 and 22. Intermediate the adjacent ends of the ribs 21 and 22 the recess 20 communicates with the ways 23 and 24 as indicated at 25 and 26. A duct 27 leads from the way 24, substantially tangential thereto. It will be observed that the inner edges of the ways 23 and 24 defined by the outer peripheral faces of the ribs 21 and 22 are substantially concentric with the axis of the shaft 18. The outer wall 28 of the rotor chamber defines the outer limits of the ways 23 and 24 and is of a spiral structure, the wall 28 being closest to the axis of shaft 18 at the junction of the way 23 and the duct 27 and receding from said axis as the wall circles about the rib 22 until said wall finally merges with the outer wall of the duct 27. The base housing 12 is provided with a peripheral flange 29 that engages the under peripheral face of the upper housing 11 whereby to provide a unitary casing 10. The base housing 12 is provided with an upwardly extending ledge 30 at the inner edge of the flange 29, that is received in a complementary recess 31 in the housing 11 whereby to provide a simple and effective aligning and sealing means between the said housings.

The rotor may be provided with a plurality of apertures 32 adjacent its axis. The lower face 33 of the rotor is provided with a plurality of centrally disposed flanges or blades 34 deposited to the front of the openings at 32 so that as the rotor is revolved,

the fluid that enters the housing by way of the port 15 is moved outwardly beyond the primary paddles 34 to a plurality of peripheral paddles 35 depending from the lower face of the rotor. The inner or primary paddles 34 operate within the recess 20 and the secondary paddles 35 operate within the ways 23 and 24. Fluid may find its way through the apertures 32 and 150 to the upper face of the rotor where the fluid is operated upon by central primary paddles or blades 36 that move the fluid outwardly for operation thereupon by secondary peripheral paddles or blades 37 that extend upwardly from the upper face 38 of the rotor. The blades 36 are contained within a recess 39 formed centrally of the housing 10 and about the axis of the rotor. The recess 39 is spaced from peripheral ways disposed outwardly or beyond the recess 39 and are set off from the central recess 39 by ribs carried by the upper housing, which ribs are disposed above the ribs 21 and 22 and are substantially identical with the ribs which they overhang, except that ribs carried by the base housing 12 are spaced further apart at the place 26 than are the ribs 61 and 62 spaced from one another above the passage 26. The ribs on the base housing 12 are spaced at considerable distance at the place 26 so that a large flow of fluid may enter the way 23 whereby to utilize the momentum imparted to the fluid discharged into the way 24 for providing a flow of large volume through the duct 27 at a comparatively low pressure. From the foregoing it will be evident that fluid moved outwardly by the central blades will move through ways 25 and 26 to the peripheral blades and when moved outwardly by the peripheral blades will pass along the wall 28 until discharged through the duct 27 into and through the pipe 40. Attention is called to the lower edges of the blades 34 in that said blades are longer near the center of the rotor and become narrower as they extend away from the center of the rotor.

A cap 41 is mounted upon the shaft 18 and serves as a closure for the upper end of the casing 10. The shaft 18 is supported by suitable ball-bearing structures 42.

By reference to Fig. 5 it will be observed that the lower face 43 of the cap 41 is provided with a spiral groove or way 44. This spiral groove bears such a relationship to the normal direction of movement of the shaft 18 that same serves to throw outwardly from the shaft 18 any dust that might find its way between the cap and the casing. In the operation of my device the shaft 18, shown in Fig. 4, will move in a clock-wise direction. Fluid contained within the receptacle 13 will enter the rotor chamber by way of the apertures in the housings. The primary blades upon the up-

per and lower faces of the rotor serve to move the fluid outward and are augmented in that effort by the peripheral blades 35 and 37. By reference to Figs. 2 and 6 it will be evident that the flow of fluid in the way 24 and in the way above said way 24 will be at considerable pressure. As this flow of fluid passes by the opening or way 26 the said flow serves to draw with it a large volume of fluid that has been fed to the way 26 by the lower blades 34 whereby the speed imparted to the fluid as it passes through the way 24 serves to impart momentum to the large mass of fluid that moves through the way 23. It therefore allows that a large flow of fluid at a comparatively low pressure, moves through the duct 27 to the pipe 40. The blades disposed upon the upper face of the rotor operate in substantially the same manner as do the blades on the lower face operate, and cooperate with the lower blades in moving the mass of fluid.

A valve 50 is ordinarily associated with the pipe 40 and controls the flow of fluid through pipe 40. When valve 50 is closed, water that enters the rotor chamber by way of the port or aperture 15 in the base housing, may escape through the apertures or ports 150, thereby precluding the fluid under pressure rising within the upper housing 11. This therefore precludes the fluid from reaching the ball bearings 42 supporting the rotor.

What I claim is:

1. In a device of the class described the combination of a casing having a rotor chamber therein, the casing comprising ribs extending into said chamber from opposite sides thereof, a rotor within the chamber and lying between the ribs extending from the opposite sides of the chamber, the ribs on opposite sides of the rotor dividing the chamber sections on opposite sides of the rotor into a central recess and a way lying outwardly of said ribs, the ribs lying on the same sides of the rotor being spaced at their ends whereby to establish communication between the central recesses and the ways disposed on a common side of the rotor, the rotor having apertures in it for establishing communication between the central recesses disposed on opposite sides of the rotor, and blades extending from opposite sides of the rotor and operating in the central recesses and in the ways.

2. In a device of the class described the combination of a casing having a rotor chamber therein, the casing comprising ribs extending into said chamber from opposite sides thereof, a rotor within the chamber and lying between the ribs extending from the opposite sides of the chamber, the ribs on opposite sides of the rotor dividing the

chamber sections on opposite sides of the rotor into a central recess and a way lying outwardly of said ribs, the ribs lying on the same sides of the rotor being spaced at their

5 ends whereby to establish communication between the central recesses and the ways disposed on a common side of the rotor, the rotor having apertures within it for establishing communication between the central 10 recesses disposed on opposite sides of the rotor, blades extending from opposite sides of the rotor and operating in the central recesses and in the ways, and means for revolving the rotor.

15 3. In a device of the class described the combination of a casing having a rotor chamber therein, the casing comprising ribs extending into said chamber from opposite sides thereof, a rotor within the chamber 20 and lying between the ribs extending from the opposite sides of the chamber, the ribs on opposite sides of the rotor dividing the chamber sections on opposite sides of the rotor into a central recess and a way lying 25 outwardly of said ribs, the ribs lying on the same sides of the rotor being spaced at their ends whereby to establish communication between the central recesses and the ways disposed on a common side of the 30 rotor, the rotor having apertures within it for establishing communication between the central recesses disposed on opposite sides of the rotor, the blades extending from opposite sides of the rotor and operating in 35 the central recesses and in the ways, the casing having a port whereby fluid may enter one of said central recesses and having a discharge duct whereby fluid may leave the ways.

40 4. In a device of the class described the combination of a casing having a rotor chamber therein, the casing comprising ribs extending into said chamber from opposite sides thereof, a rotor within the chamber 45 and lying between the ribs extending from the opposite sides of the chamber, the ribs on opposite sides of the rotor dividing the chamber sections on opposite sides of the rotor into a central recess and a way lying 50 outwardly of said ribs, the ribs lying on the same sides of the rotor being spaced at their ends whereby to establish communication between the central recesses and the ways disposed on a common side of the rotor, 55 the rotor having apertures within it for establishing communication between the central recesses disposed on opposite sides of the rotor, and blades extending from opposite sides of the rotor and operating in 60 the central recesses and in the ways, the casing having a port whereby fluid may enter one of said central recesses and having a discharge duct whereby fluid may leave the ways, the ribs disposed on that side of 65 the casing having said port provided there-

in having their ends spaced at a distance greater than the distance between the ends of the ribs disposed on the opposite side of the rotor.

5. In a device of the class described the combination of a casing having a rotor chamber therein, the casing comprising ribs extending into said chamber from opposite sides thereof, a rotor within the chamber and lying between the ribs extending from the opposite sides of the chamber, the ribs on opposite sides of the rotor dividing the chamber sections on opposite sides of the rotor into a central recess and a way lying 70 outwardly of said ribs, the ribs lying on the same sides of the rotor being spaced at their ends whereby to establish communication between the central recesses and the ways disposed on a common side of the rotor, the casing having ports therein for effecting 75 communication through the casing with the opposed sections of the chamber, and blades extending from opposite sides of the rotor and operating in the central recesses and in the ways.

80 6. In a device of the class described the combination of a casing having a rotor chamber therein, the casing comprising ribs extending into said chamber from opposite sides thereof, a rotor within the chamber 90 and lying between the ribs extending from the opposite sides of the chamber, the ribs on opposite sides of the rotor dividing the chamber sections on opposite sides of the rotor into a central recess and a way lying 95 outwardly of said ribs, the ribs lying on the same sides of the rotor being spaced at their ends whereby to establish communication between the central recesses and the ways disposed on a common side of the 100 rotor, the casing having ports therein for effecting communication through the casing with the opposed sections of the chamber, blades extending from opposite sides of the rotor and operating in the central recesses 105 and in the ways, and means for revolving the rotor.

110 7. In a device of the class described the combination of a casing having a rotor chamber therein, the casing comprising ribs 115 extending into said chamber from opposite sides thereof, a rotor within the chamber and lying between the ribs extending from the opposite sides of the chamber, the ribs on opposite sides of the rotor dividing the 120 chamber sections on opposite sides of the rotor into a central recess and a way lying outwardly of said ribs, the ribs lying on the same sides of the rotor being spaced at their ends whereby to establish communication 125 between the central recesses and the ways disposed on a common side of the rotor, the blades extending from opposite sides of the rotor and operating in the central recesses and in the ways, the casing 130

having ports whereby fluid may enter said central recesses and having a discharge duct whereby fluid may leave the ways.

8. In a device of the class described the combination of a casing having a rotor chamber therein, the casing comprising ribs extending into said chamber from opposite sides thereof, a rotor within the chamber and lying between the ribs extending from the opposite sides of the chamber, the ribs on opposite sides of the rotor dividing the chamber sections on opposite sides of the rotor into a central recess and a way lying outwardly of said ribs, the ribs lying on the same sides of the rotor being spaced at their ends whereby to establish communication between the central recesses and the ways

disposed on a common side of the rotor, and blades extending from opposite sides of the rotor and operating in the central recesses and in the ways, the casing having ports whereby fluid may enter said central recesses and having a discharge duct whereby fluid may leave the ways, the ribs disposed on that side of the casing having said port provided therein having their ends spaced at a distance greater than the distance between the ends of the ribs disposed on the opposite side of the rotor.

In testimony whereof, I have hereunto subscribed my name this 9th day of April, 1924.

VICTOR ROSENHAGEN.
